CLAIM

The ornamental design for a shower caddy, as shown and described.

DESCRIPTION

FIG. 1 is a perspective view of a shower caddy; FIG. 2 is a front view of the shower caddy of FIG. 1; FIG. 3 is a rear view of the shower caddy of FIG. 1; FIG. 4 is a right side view of the shower caddy of FIG. 1; FIG. 5 is a left side view of the shower caddy of FIG. 1; FIG. 6 is a top view of the shower caddy of FIG. 1; and, FIG. 7 is a bottom view of the shower caddy of FIG. 1. Any broken lines are for the purpose of illustrating portions of the shower caddy that form no part of the claimed design.
